LIPSTICK HOLDER

Samuel Segal, New York, N. Y., assignor of forty per cent to Harry Rubin, New York, N. Y., and twenty per cent to Charles M. Palmer, Washington, D. C.

Application March 8, 1947, Serial No. 733,311

21 Claims. (Cl. 206—56)

1

This invention is a lipstick holder and the dominant object thereof is realized in the provision of effective means automatically operable upon mounting of closure means in the form of a cap on the jacket of the holder to deflect spring detent means for removably interlocking with a rotatable barrel in which a lipstick sustaining cup is slidably and rotatably guided to preclude accidental displacement of the cup and concomitantly preventing involuntary removal of the cap by the lipstick. Another object of the invention is to lock the cup against upward displacement when the closure means is shifted downwardly on the jacket. Another object is to permit rotation of the cup actuating means upon removal of the closure from the jacket of the holder. Another object resides in the provision of locking means responsive on the mounting of the cap on the jacket to prevent rotation of the barrel and consequently of the cup at a time when the latter is at its lowest position within the jacket. Another object is to preclude fully closing of the cap unless the lipstick seat of the displaceable cup is at the lowest part of the cam slot of a split bearing rotatably guiding the barrel and firmly retained by the surrounding jacket. Other important objects, features and functional and structural advantages will be apparent from the following detailed description taken with the accompanying drawings wherein:

Fig. 1 is a perspective view of the lipstick holder according to one embodiment of the invention however showing the cap removed therefrom.

Fig. 2 is an exploded and perspective view of the lipstick holder illustrated in Fig. 1.

Fig. 3 is a side elevational view of the lipstick holder shown in Fig. 1, however partly broken away and partly in section to illustrate the internal construction.

Fig. 4 is a view similar to Fig. 3 but with the cap mounted on the lipstick holder.

Fig. 4A is a fragmentary sectional view on the line 4A—4A of Fig. 4.

Fig. 5 is a horizontal sectional view on the line 5—5 of Fig. 4.

Fig. 6 is a view similar to Fig. 3 but illustrating another embodiment according to the invention.

Fig. 6A is a side view of the spring locking detent employed in the form shown in Fig. 6.

Fig. 7 is a horizontal sectional view on the line 7—7 of Fig. 6.

Fig. 8 is a fragmentary view of Fig. 6 however illustrating the cap mounted on the holder and the locking detent in position to preclude rota-

2

tion of and upward displacement of the lipstick carrying cup.

Fig. 9 is a front view of Fig. 6.

Fig. 10 is a view similar to Fig. 3 but illustrating another form of holder but with the cap removed therefrom.

Fig. 11 is a view similar to Fig. 10 but with the detent actuating cap mounted on the jacket to preclude elevation of the lipstick sustaining cup when the latter is at its lowest position within the jacket.

Fig. 12 is a view similar to Fig. 10 however illustrating another holder in accordance with my invention.

Fig. 13 is a view similar to Fig. 12 but with the removable cap positioned on the holder to prevent rotation of the lipstick sustaining cup.

Fig. 14 is an exploded and perspective view of a lipstick holder according to the preferred embodiment of my invention.

Fig. 15 is an elevational view of the holder shown in Fig. 14, partly in section and partly broken away but with the cap however removed.

Fig. 16 is a view along the lines of Fig. 15 but showing the cap mounted on the holder to lock the rotatable barrel against rotation, and

Fig. 17 is a sectional view on the line 17—17 of Fig. 16.

In the embodiment according to Figs. 1 to 5 inclusive the holder H is characterized by a cylindrical barrel or shell S having the relatively large knob or manipulating portion K appropriately fastened thereto. This shell also embodies the vertically arranged slot 10 and the keeper means or opening 11 and the struck out overhanging annular but hollow bead 12.

Slidably guided within the barrel or shell S is the cylindrical lipstick receiving and sustaining cup 14 having appropriately secured therein the diametrically arranged pin 15 having a terminal 16 projecting into the elongated slot 10 whose spaced and vertical walls movably guide pin 15 relative to the shell S.

The terminal or projecting means 16 of the pin or seat 15 also projects into the helicoidal cam slot 17 of the cylindrical sheet metal bearing or sleeve 18 which closely encompasses shell S. Sleeve 18 is interrupted by the elongated vertical slot or gap 19 defining spaced and vertically disposed walls in turn interrupted by the aligned notches or gaps 20.

For holding the normally expanded sleeve or bearing 18 slightly compressed about the shell S, a hollow cylindrical retaining jacket 21 is utilized. More specifically, jacket 21 frictionally engages

the outer surface of the sleeve 18 to hold the latter in place between the overhanging bead 12 and the knob K, the arrangement being such that although the spiral cut sleeve 18 is held anchored by the retaining jacket, nevertheless this sleeve constitutes a bearing within which the shell or barrel S may be rotated relative to both the sleeve 18 and the retaining jacket upon rotating or manipulating of the knob K.

The cup 14 bodily rotates with shell S since terminal 16 is interlocked with the walls of the vertical slot 10. This cup however is also slidably mounted within the bore of the shell or barrel S and since the terminal 16 projects into the spiral slot 17, the spaced cam walls of the latter actuate terminal 16 upon rotation of the barrel or shell S to either elevate or lower the cup 14 relative to the vertical slot 10 depending upon the direction of rotation of the knob K but at this time the cup 14 also bodily rotates with the barrel S. Consequently if a lipstick L be seated on the pin 15 it may be projected out of the barrel S and if projected it may be thereafter retracted into the barrel upon rotation of knob K.

An annular band B frictionally engages the lower portion of the jacket 21 and serves as a stop for the cylindrical closure or cap C.

With the cup 14 in its lowest position within the barrel S, the terminal 16 of the cross pin or seat 15 is at the lowest part of the cam or spiral slot 17 at which time opening or socket 11 of the rotatable barrel S registers or is in line with the notches 20 of the bearing or sleeve 18. Also at this time spring lock detent or pivoted arm 23 which according to the form illustrated in Figs. 1-5 is struck out of the sheet metal jacket 21 is out of the cooperating opening or keeper 11 of the barrel and the aligned notches 20 of the bearing 18. Specifically the spaced kerfs 24 are formed in the jacket after which the lower portion of resilient detent 23 is provided with the reflexed nose portion 25 which when the cap C be removed from jacket 21, automatically retracts outwardly to unlock from the barrel or shell 18 and consequently the latter may be rotated upon manipulation of the knob K.

If the cap C be mounted on the jacket 21 and moved downwardly (Fig. 4) it actuates the overhanging nose or cam portion 25 of the locking detent 23, causing the latter to be deflected inwardly, thereby entering keeper or opening 11 of the barrel 18, thus removably interlocking the latter to prevent its rotation. By this action the lipstick carrying cup when in its lowest position is prevented from being accidentally raised. The cap C may be said to operate the spring cantilever detent 23 and has a friction fit with the jacket. In addition the reactive thrust on the part of the detent 25 against the cap C when the latter is fully on the jacket forms supplementary means to preclude accidental removal therefrom from the jacket.

Once the cap C is removed from the jacket, cam 25 automatically and resiliently snaps out of the socket or opening 11 of the barrel S and clear of the sleeve 18. The barrel is now unlocked and knob K may again be rotated to lift stick L seated on pin 15 out of the barrel.

To facilitate proper assembly of the retaining jacket 21 on the cam slotted sleeve 18, spaced 7
indents 26 and 27 are provided at the upper
part of the jacket and a single detent 28 is pro-
vided at the lower part of the jacket. The in-
dents 26 and 27 in fact are projections extend-
ing inwardly of the body of the jacket while the 7

detent 28 projects outwardly of the jacket as shown. Indent or projection 26 and the indent or projection 28 are in vertical alinement.

In this matter of assembly, if the cam slotted sleeve or bearing 18 be mounted on the barrel S, the jacket 21 may be quickly lined up with sleeve 18 by first arranging the alined projections 26 and 28 in line with the vertical slot 19 of the sleeve and thereafter sliding jacket 21 over the sleeve 18 which becomes compressed although the upper projection 26 snaps between the walls of slot or gap 19 of the sleeve (Fig. 4A) to interlock the latter with the jacket to preclude accidental rotation of the jacket relative to the sleeve. As a further means to preclude slippage of the jacket 21 relative to cap 18, the indent or projection 27 as is well understood frictionally cooperates with the cap C to retain it in place and against the band B.

By the present invention the lipstick L cannot be accidentally projected out of the holder when the cap is mounted on the jacket nor can the cap be accidentally withdrawn. Thus the possibility of the cap falling off the holder is materially reduced. Consequently accidental projection of the lipstick out of the holder is avoided.

In the form according to Figs. 6 to 9 inclusive the spring detent 23' is a separate member and not formed out of the body of the jacket 21'. After the jacket 21' is assembled on the sleeve or bearing 18', the shank 30' of the spring detent 23' is inserted between the walls of slot 19' through the lower opening 31' in the jacket 21' (Fig. 9) until it meets the stop bead 12' (Fig. 6). Projection or indent 26' aids to hold shank 30' in place and shank 30' also is disposed within slot 19' and interlocks with the walls of the latter to prevent rotation of the sleeve 18'. The reflexed nose 25' of detent 23' normally projects outside of the jacket 21' and is free of the opening or keeper 11' of the barrel or shell S' and the opening 33' in the cup 14'. Thus the barrel is unlocked and the cup is free to be displaced upwardly. Knob K' may therefore be turned for slidably and rotatably displacing the cup. If however the cap C' be mounted on the jacket 21', the nose 25' of the resilient detent 23' is deflected inwardly to interlock with the wall of keeper or opening 11' of the barrel S' and with the wall of opening 33' in the cup. With nose 25' interlocked with opening 11', the barrel S is locked against rotation. Hence the cup 14' cannot be actuated and at this time the cup is also trapped by the nose 25' against upward displacement. Otherwise the embodiment illustrated in Figs. 6 to 9 inclusive is along the lines of the form disclosed in connection with Figs. 1-5.

In Figs. 10 and 11, shell or barrel S^a has its keeper or opening 11^a adjacent the bead 12^a and locking detent 23^a is struck out but integrally merged with the lower part jacket 21^a and has its nose 25^a at the upper part thereof and receivable in notches 23^a and immediately awaiting to be actuated by the cap C^a for interlocking with the opening 11^a of the rotatable barrel S^a . In Figs. 10 and 11, projections 26^a and 28^a are directly impressed on the shank of detent 23^a . Projection 26^a interlocks with the walls of slot 19^a of the sleeve 18^a to prevent rotation of the latter relative to the jacket 21^a and projection 28^a frictionally cooperates with the cap C^a to preclude accidental dislodgement of the latter. In other aspects the species illustrated in Figs. 10 and 11 is along the lines of Figs. 1-5.

In the form according to Figs. 12 and 13 the spring detent 23^b forms no part of the jacket 21^b and the shank 40^b thereof is inserted into opening 41^b at the upper end of the jacket and has its lower end seated on the knob or flange K^b. The nose or offset portion 25^b normally is free of the keeper or opening 11^b of the barrel S^b and hence the knob K^b may be rotated for elevating or lowering cup 14^b and in its most lowered position within the barrel, the latter is locked against rotation immediately after the cap C^b is mounted on the jacket 21^b, thus deflecting the nose 25^b inwardly to removably interlock with the wall of opening 11^b. It follows that the cup 14^b cannot be actuated or displaced in that it is interlocked with the locked barrel S^b. In other aspects the form illustrated in Figs. 12 and 13 is substantially along the lines of the form illustrated in Figs. 10 and 11.

In the preferred embodiment illustrated in Figs. 14 to 17 inclusive, the keeper or opening or aperture 11² is in the barrel S² and is rectangular for removably interlocking with the nose or cam portion 25² of the spring detent 23² which is interposed between the spaced sides of the gap or slot 19² of the cam slotted bearing 18². The lower end of the shank of the detent 23² is provided with an outwardly extending lug 50² removably received in and interlocked with the walls of the notch 51² in the annular fixed retaining band B² and the aligned notch 52² in the jacket 21². Lug 50² is also seated on the knob K². If the spring detent is interlocked with the walls of the aligned notches 51² and 52², it is prevented from being vertically displaced relative to the jacket. This detent also serves to interlock the sleeve 18² against rotation relative to the jacket. Nose 25² normally slightly overhangs the non-circular opening 53² at the upper part of the jacket but is adapted to be fully cammed or sprung therein and into the elongated slot or opening 11² of the rotatable barrel S² when the cap C² is mounted on the jacket 21² and moved downwardly. Thus the barrel S² is locked immediately after the cap C² is applied to the retaining jacket 21². Detent or projection 54² extending from the jacket frictionally cooperates with the cap C² to preclude accidental removal therefrom. In other aspects the form illustrated in Figs. 14 to 17 is substantially along the lines of the form shown in Figs. 12 and 13 although in the matter of assembling of the embodiment according to Figs. 14 to 17, the detent 23² is positioned in the gap 19² after the sleeve or bearing 18² is mounted on the barrel S². Thereafter the jacket 21² is mounted on the bearing 18² so that opening 53² lines up with nose 25² and subsequently the jacket is moved downwardly permitting the side walls of the aligned notches 51² and 52² to straddle the lug 50² about the time nose 25² is received and snaps into the opening 53².

In all the embodiments disclosed, the rotatable barrel is locked against rotation after the cap is mounted on the jacket and moved downwardly therealong and by this action the lipstick carrying cup is thus held in its lowermost position against upward vertical displacement. Or in other words, in all the embodiments disclosed locking of the barrel or shell against rotation due to the action of the spring locking detent when actuated by the cap, takes place when the lipstick seat or pin is at the lower part of the cam slot in the sleeve or bearing. It follows that the knob cannot be accidentally rotated for effecting displacement of the lipstick out of the jacket when

the cap is mounted on the latter, thus avoiding the possibility of needlessly staining or coloring on the part of the lipstick.

Unless the cup is at its lowest part of the barrel S, that is, unless projection as 16 is at the predetermined lowest part of the cam slot of the bearing, the cap C cannot be fully closed, namely, to reach the fixed annular band B. It is only when the seat or pin 16 is at the lowest part of the cam slot that the keeper means or aperture as 11 becomes in alignment or registration with opening 53² of the jacket to permit reception of the reflexed nose portion of the spring locking detent. Otherwise the reflexed portion acts as a stop preventing the cap to be shifted there beyond. This is true of all of the embodiments disclosed.

Various changes may be made in details of construction and arrangement of parts without departing from the spirit of the invention or sacrificing any of the advantages thereof inherent therein.

I claim:

1. In a holder, a cup having means for retaining a lipstick and having projecting means, a rotatable barrel surrounding said cup and having keeper means and including means movably guiding said projecting means vertically of said barrel, a bearing surrounding and rotatably guiding said barrel and including a spiral slot having walls severally cooperating with said projecting means upon rotation of said barrel relative to said bearing for displacing said cup and including spaced sides defining an elongated gap, a jacket closely surrounding said bearing and embodying an opening, a spring detent having a shank within said jacket and mounted within said gap and having a reflexed portion normally projecting at least in part through said opening to outwardly overhang said jacket, means to prevent rotation of said jacket relative to said bearing, and a cap removably mounted on said jacket and having means for actuating said reflexed portion into said opening and into said keeper means to preclude rotation of said barrel relative to said jacket.

2. In a holder, a cup having means for sustaining a lipstick and comprising projecting means, a rotatable barrel surrounding said cup and having keeper means and including means movably guiding said projecting means vertically of said barrel, a bearing surrounding and rotatably guiding said barrel and including a spiral slot having walls severally cooperating with said projecting means upon rotation of said barrel relative to said bearing for displacing said cup and including spaced sides defining an elongated gap, a jacket closely surrounding said bearing and embodying an opening and a notch, a spring detent having a shank within said jacket and mounted within said gap and having a reflexed portion normally projecting at least in part through said opening to outwardly overhang said jacket and having outwardly projecting means extending into said notch to preclude rotation of said jacket relative to said bearing, and a cap removably mounted on said jacket and having means for actuating said reflexed portion into said opening and into said keeper means when said first-mentioned projecting means is at the lower part of said slot to preclude rotation of said barrel relative to said jacket.

3. In a holder, a cup having a seat for sustaining a lipstick and comprising terminal means overhanging said cup, a rotatable barrel surround-

ing said cup and having keeper means and including means movably guiding said terminal means vertically of said barrel, a bearing surrounding and rotatably guiding said barrel and including a spiral slot having walls severally cooperating with said terminal means upon rotation of said barrel relative to said bearing for displacing said cup and including spaced sides defining an elongated gap, a jacket closely surrounding said bearing and embodying an opening at the upper part thereof and a notch at the lower part thereof, a spring detent having a shank within said jacket and mounted within said gap and having a reflexed portion at its upper end and normally projecting at least in part through said opening to outwardly overhang said jacket and having at its lower end outwardly projecting means extending into said notch to preclude rotation of said jacket relative to said bearing, and a cap removably mounted on said jacket and having means for actuating said reflexed portion into said opening and into said keeper means when said terminal means is at the lower part of said slot to preclude rotation of said barrel relative to said jacket.

4. In a holder, a cup having a seat for sustaining a lipstick and comprising terminal means overhanging said cup, a rotatable barrel surrounding said cup and having keeper means and including means movably guiding said terminal means vertically of said barrel, a bearing surrounding and rotatably guiding said barrel and including a spiral slot having walls severally cooperating with said terminal means upon rotation of said barrel relative to said bearing for displacing said cup and including spaced sides defining an elongated gap, a jacket closely surrounding said bearing and embodying an opening at the upper part thereof and a notch at the lower part thereof, a spring detent having a shank within said jacket and mounted within said gap and having a reflexed portion at its upper end and normally projecting at least in part through said opening to outwardly overhang said jacket and having at its lower end outwardly projecting means extending into said notch to preclude rotation of said jacket relative to said bearing, retaining means surrounding said jacket and interlocking with said outwardly projecting means, and a cap removably mounted on said jacket and having means for actuating said reflexed portion into said opening and into said keeper means when said terminal means is at the lower part of said slot to preclude rotation of said barrel relative to said jacket.

5. In a holder, a cup having a pin for sustaining a lipstick and comprising terminal means overhanging said cup, a rotatable barrel surrounding said cup and having keeper means and including means movably guiding said terminal means vertically of said barrel and including at its lower end a knob, a bearing surrounding and rotatably guiding said barrel and including a spiral slot having walls severally cooperating with said terminal means upon rotation of said barrel relative to said bearing for displacing said cup and including spaced sides defining an elongated gap, a jacket closely surrounding said bearing and embodying a notch at the lower part thereof and embodying an opening at the upper part thereof and adapted to register with said keeper means when said seat is at the bottom part of said slot, a spring detent having a shank within said jacket and mounted within said gap and having a reflexed portion at its upper end and normally

projecting at least in part through said opening to outwardly overhang said jacket and having at its lower end outwardly projecting means seated on said knob and extending into said notch to preclude rotation of said jacket relative to said bearing, and a cap removably mounted on said jacket and having means for actuating said reflexed portion into said opening and into said keeper means when said terminal means is at the lower part of said slot to preclude rotation of said barrel relative to said jacket.

6. In a holder, a cup having a pin for sustaining a lipstick and having terminal means overhanging said cup, a rotatable barrel surrounding said cup and having keeper means and including means movably guiding said terminal means vertically of said barrel and including at its lower end a manipulatable knob, a bearing surrounding and rotatably guiding said barrel and including a spiral slot having walls severally cooperating with said terminal means upon rotation of said barrel relative to said bearing for displacing said cup and including spaced sides defining an elongated gap, a jacket closely surrounding said bearing and embodying a notch at the lower part thereof and embodying an opening at the upper part thereof and adapted to register with said keeper means when said terminal means is at the bottom part of said slot, a spring detent having a rectilinear shank free of and within said jacket and mounted within said gap and having a reflexed portion at its upper end and normally projecting at least in part through said opening to outwardly overhang said jacket and having at its lower end outwardly projecting means seated on the upper part of said knob and extending into said notch to preclude rotation of said jacket relative to said bearing, retaining means having means interlocking with said outwardly projecting means and seated on said knob and surrounding said jacket, and a cap removably mounted on said jacket and having means for actuating said reflexed portion into said opening and into said keeper means when said terminal means is at the lower part of said slot to preclude rotation of said barrel relative to said jacket.

7. In a holder, a cup having means for sustaining a lipstick and including projecting means, a barrel surrounding said cup and having keeper means and including means movably guiding said projecting means, a bearing about and rotatably guiding said barrel and including a spiral slot having walls severally cooperating with said projecting means for displacing said cup and including spaced sides defining an elongated gap, a jacket closely surrounding said bearing and including an opening, and spring locking means having a shank mounted inside of and concealed by said jacket and disposed within said gap and having a reflexed portion in part accessible outside of said opening and overhanging said jacket.

8. In a holder, a cup having means for sustaining a lipstick and including projecting means, a barrel surrounding said cup and having keeper means and including means movably guiding said projecting means, a bearing about and rotatably guiding said barrel and including a spiral slot having walls severally cooperating with said projecting means for displacing said cup and including spaced sides defining an elongated gap, a jacket closely surrounding said bearing and including an opening, spring locking means having a shank mounted inside of and concealed by said jacket and disposed within said gap and having a reflexed portion in part accessible outside of

said opening and overhanging said jacket, and a cap removably mounted on said jacket and having means for actuating said reflexed portion into said keeper means to preclude rotation of said barrel relative to said jacket.

9. The holder according to claim 8 wherein said reflexed portion is in alinement with said keeper means but out of the latter when the cap is removed from the jacket.

10. The holder according to claim 9 characterized in that the locking means is displaced in a direction within the jacket to enter the keeper means when the cap is slidably moved downwardly along the jacket to prevent rotation of the barrel at a time when said projecting means is at the lower part of the spiral slot.

11. The holder according to claim 7 characterized further in that said keeper means is a vertical slot in which the spring locking means may be partly disposed and the jacket embodies a notch to retain a lug of the locking means.

12. The holder according to claim 11 wherein the notch is disposed at the lower part of the jacket and the walls thereof interlock with the lug to retain the spring locking means against upward vertical displacement.

13. The holder according to claim 7 wherein said opening is adapted to be disposed in registration with said keeper means when said projecting means is at the lower part of said slot and the reflexed portion being normally out of said keeper means and partly projecting beyond said opening.

14. The holder according to claim 7 wherein the locking means is independent of the jacket but is retained between the barrel and jacket and by the bearing.

15. The holder according to claim 7 wherein the jacket embodies means projecting into said gap for alining thereof relative to said bearing.

16. The holder according to claim 7 wherein said reflexed portion is projectible only into said keeper means when said projecting means is at the lowest part of said slot.

17. The holder according to claim 16 characterized in that said barrel limits inward displacement of said reflexed portion at a time when said keeper means is out of registration with said opening.

18. The holder according to claim 8 wherein said reflexed portion characterizes a stop to preclude complete mounting of said cap on the jacket at a time when said keeper means is out of registration with said opening.

19. A holder of the class described comprising a pair of telescoping relatively rotatable tubular members, a carrier within said members, cooperative means between said members and carrier for advancing and retracting said carrier coincident with the relative rotation of said members, a closure cap for telescoping over said members, an opening in the inner member independent of said advancing and retracting means, a locking latch carried by the outer member comprising a knee portion normally sprung outwardly of the outer surface of said inner member, a shell telescoping said members, said shell having an opening through which said knee portion of said latch protrudes outwardly beyond the outer surface thereof and in the path of the telescoping cap, whereby the latch is sprung inwardly of the members by engagement with said cap to enter said opening and interlock with the inner member

and prevent relative rotation of said members when said closure cap is telescoped over said members.

20. A holder of the class described comprising a pair of telescoping relatively rotatable tubular members, a carrier within said members, cooperative means between said members and carrier for advancing and retracting said carrier coincident with the relative rotation of said members, a closure cap for telescoping over said members, an opening in the inner member independent of said advancing and retracting means, a separate locking latch having a shank and knee portion carried by the outer member, said knee portion being normally sprung outwardly of the outer surface of said inner member, a shell telescoping said members, an opening in said outer member in which the shank portion of said separate latch is located and held between said shell and inner member, said shell having an opening through which said knee portion of said latch protrudes outwardly beyond the outer surface thereof and in the path of the telescoping cap, whereby the latch is sprung inwardly of the members by engagement with said cap to enter said opening and interlock with the inner member and prevent relative rotation of said members when said closure cap is telescoped over said members.

21. In a holder, a cylindrical cup having an inside diametrically arranged pin for sustaining a lipstick and said pin having a part projecting outside of said cup, a rotatable cylindrical barrel surrounding said cup and having an aperture at the upper part thereof and including means independent of said aperture movably guiding said pin vertically of said barrel and including at its lower end an accessible knob, a cylindrical bearing surrounding and rotatably guiding said barrel and including a spiral slot having walls severally cooperating with said part upon rotation of said barrel relative to said bearing for vertically displacing said cup and including spaced vertically arranged sides defining an elongated gap disposed along the entire length of said bearing, a cylindrical jacket closely surrounding said bearing and embodying a notch at the lower part thereof and embodying an opening at the upper part thereof and adapted to register with said aperture only when said pin is at the bottom part of said spiral slot, a spring detent having a rectilinear shank within said jacket and mounted within said gap and having an outwardly overhanging reflexed portion at its upper end and normally projecting at least in part through said opening to outwardly overhang said jacket and having at its lower end outwardly projecting means seated on said knob and extending into said notch to preclude rotation of said jacket relative to said bearing, and a cap removably mounted on said jacket and having means for actuating said reflexed portion into said opening and into said aperture when said pin is at the bottom part of said spiral slot to preclude rotation of said barrel relative to said jacket.
